UNITED STATES PATENT OFFICE.

ELSA TENNHARDT, OF NEW YORK, N. Y., ASSIGNOR TO E. & J. BASS, INC., A CORPORATION OF NEW YORK.

DESIGN FOR A DISH OR ARTICLE OF ANALOGOUS NATURE.

Application filed May 23, 1928. Serial No. 26,830. Term of patent 3½ years.

To all whom it may concern:

Be it known that I, ELSA TENNHARDT, a citizen of the United States of America, and a resident of the city, county, and State of New York, have invented a new, original, and ornamental Design for a Dish or Article of Analogous Nature, of which the following is a specification, reference being had to the accompanying drawing, forming a part hereof.

In the drawings:

Figure 1 is a top plan view of the dish or article of analogous nature; and

Figure 2 is a perspective view of the same. The dominant feature of the design resides in the employment of long triangular areas A of contrasting color placed about the edges of a triangular pyramid and arranged so that the apex of one triangular area is near the base of the next triangular area.

I claim:

The ornamental design for a dish or article of analogous nature substantially as shown and described.

ELSA TENNHARDT.
